UNITED STATES PATENT OFFICE.

CLAYTON E. WYRICK, OF ALBANY, NEW YORK, ASSIGNOR TO MULTI-PRINT SYSTEM CO., INC., OF CHICAGO, ILLINOIS, A CORPORATION OF SOUTH DAKOTA.

PRINTING AND SERVING MACHINE.

1,391,356.

Specification of Letters Patent. Patented Sept. 20, 1921.

Application filed December 7, 1918. Serial No. 265,772.

To all whom it may concern:

Be it known that I, CLAYTON E. WYRICK, a citizen of the United States, residing at Albany, county of Albany, State of New York, have invented a certain new and useful Improvement in Printing and Serving Machines, and declare the following to be a full, clear, and exact description of the same, such as will enable others skilled in the art 10 to which it pertains to make and use the same, reference being had to the accompanying drawings, which form a part of this specification.

This invention relates to printing and serving machines and the principal object is to provide a locking device of simple construction preventing the discharge of more than the desired length of the printed strip from the register. The lock is of particular utility in conjunction with the operating of self-printing registers by means of which the paper strips are printed as they are withdrawn from the register and a feature of this device is a lock adapted for 20 actuation by the revolution of the printing roll as is hereinafter more particularly shown and described. A further object of the invention is a lock of the character described which may be released from the exterior of the machine by the operator at the time it is desired to withdraw a printed sheet and that automatically locks as the predetermined length of the sheet is discharged. These and other objects and 30 several novel features of the invention are hereinafter more fully described and claimed and shown in the accompanying drawing in which—

Figure 1 is an elevation partly in section 40 of an autographic register and locking device embodying my invention.

Fig. 2 is an elevation of the locking arrangement in the locked position.

Fig. 3 is a similar elevation showing the 45 parts in unlocked position.

The register shown is of the self-printing type having a printing roll 1 rotatably mounted in the frame of the machine and an inking roll 2 therefor. Several paper rolls may be provided in the device, two of which only, 3 and 4 are here shown. The paper strips, indicated by the lines 5 and 6, on withdrawal in printing contact with the roller 1, the direction of rotation of which 50 is shown by the arrow therein and the direc-

tion of movement of paper strips being shown by arrows contiguous thereto. Other paper rolls may be provided as for instance as is shown in U. S. Patent No. 1,256,078 of February 12, 1918 in which a third roll 60 of blank paper is provided. The two rolls shown here, however, serve to illustrate the principle of operation of the invention herein disclosed. These paper strips pass about the idler rollers to the upper part of 65 the frame running over a writing table 7 with a carbon paper sheet therebetween. The upper cover 9 of register has an opening exposing the upper strips to view for the purpose of writing thereon and the upper strip in the arrangement shown is withdrawn as indicated at 10, while the lower strip is taken up on a rewind roll 11 at the forward end of the machine. The paper strips are drawn from the rolls by means 70 of the roll 12 and the lower roll indicated at 13 which has a handle 14 and the upper roll engages therewith under sufficient tension to withdraw the paper from the rolls and rotate the printing roller or the printing roller may be directly driven by the operating roll if desired.

The printing roll here shown is to be considered as one in which the type or printing surface is of such length to require one 85 revolution of the roll to impress the same upon the strips. The printing surface may, however, be formed of two or more duplicate portions thereon so that upon revolution of the printing roll two or more impressions are made upon the paper strips and the function of the locking device is to stop the 90 unwinding of the strips from the roll and discharge thereof from the machine between each separate impression on the strip. For 95 this purpose the printing roll shaft is provided with a cam member 15 having a notch 16 therein and a lever 17 is pivotally supported on a shaft 18 having an end 19 adapted to engage the said notch 16 of the cam. 100 As here shown there is but one notch 16 provided, but in case the printing surface is duplicate or triplicate in character the cam should be provided with an equal number of notches as will be readily understood.

The operating roll 13 is provided at one end with a toothed wheel 20 and the forward end of the lever 17 is provided with a tooth 21 adapted to engage between the teeth of the wheel 20. The forward end of the lever 110

in the construction here shown is provided with an upward extending arm 22 and a pin 23 is provided in the upper part 24 of the case covering the tension roller 12, the 5 lower end of which engages the arm 22. By depressing the pin 23 the tooth 21 of the lever may be withdrawn from the teeth of the wheel 20. Let it be supposed that the lock is set with the tooth 21 engaging with 10 the gear 20 as shown in Fig. 2. Under this condition the rollers 13 and 12 may not be rotated being held by the tooth 21. In order to rotate the same the pin 23 is depressed as indicated in Fig. 3, withdrawing 15 the tooth 21 from the gear wheel and allowing the rolls 12 and 13 to be rotated to withdraw paper from the paper rolls. This pin should be held depressed upon beginning 20 of rotation of roll 13 by the handle 14 for a slight period to allow the high part of the cam member 15 to engage beneath the end 19 of the locking lever which is held in the position shown in Fig. 3 by the cam. The rolls 13 and 12 may then be turned with- 25 drawing the paper until the notch 16 of the cam again comes beneath the end 19 of the lever, which by action of the spring 25, draws the forward end of the lever upward forcing the tooth 21 into engagement with 30 the gear so preventing further rotation. A strip may then be torn off as is usual with the registers of this type and the parts are again ready for operation by depression of the pin 23.

35 By the arrangement described the use of a notch on a cam for each separate printing surface on the printing roller the discharge of strips will be halted at predetermined intervals determined by the length of the 40 printed portions and the arrangements of parts is such that the strips are discharged in such manner that they may be severed between each impression thereon.

In the above described method it is necessary to hold the pin down until the printing roller has been turned to such an extent that the cam is in a position to hold the lever with the tooth thereon out of engagement with the gear. This may cause inconvenience 45 through negligence of the operator releasing the pin sooner than it is designed to be released. Mechanism may be provided to prevent immediate return of the locking member to position on release of the pin 23. For 50 this purpose I have provided a device consisting of a member 30 pivotally positioned and carried by the frame of the machine and provided with a portion 32 extending over the forward toothed end the bar 17 and normally lying in contact therewith. Pivotally mounted on this bar is a serrated-edged segment 33 having an extension 34 extending beyond the pivot as shown. A spring 35 is provided connected with the member 30 at 55 one end and to this extension 34 at the other

end tending to draw the parts to position as shown in Fig. 1 when free to do so. When the parts are in the locked position as shown in Fig. 2 the segment 33 is in its upward position as shown with the lower edge or 70 point 36 just resting on the gear 13. On depressing the pin 23 this segment is released to actuation by the spring 35 which draws it to position shown in Fig. 1. The toothed portion 33 is on a radius eccentric 75 to the member 30 which swings on the pivot 31 in moving to the position shown in Fig. 1. The serrated edge thus lies in engagement with the toothed edge of the wheel 13 and a spring 25 of the lever 17, by reason of 80 this engagement, may not draw the lever 17 to locked position. By rotation of the wheel 13, however, the segment 33 is turned on its pivot after the manner shown in Fig. 2, which releases the lever 17 to actuation by 85 the spring 25. By this arrangement the gear wheel is rotated for a distance before the lever is released to action by the spring 25. This interval of retard allows the printing roller to be turned and the cam thereon 90 brought to position to hold the lever in unlocked position, enabling the paper to be withdrawn without the necessity of holding the pin 23 for any predetermined period. Under the above condition with the retarding 95 apparatus used in conjunction with the locking lever, the pin may be simply depressed and the paper be withdrawn without further attention to the locking device as the retarding device is automatic in operation. It is also evident that the locking device is operable whether the retarding device is or is not used.

100 From the foregoing description it is evident that the arrangement is simple and 105 efficient in character and inexpensive to manufacture, and further that a waste of paper is avoided in that the strip is stopped in movement between each impression thereon and thus the withdrawing rolls 12 and 13 110 are stopped in operation so that a portion only of a strip having a single impression may be projected at a time. Without the locking device the operator could turn the rolls to project more than one impression, 115 that is an impression and part of another, causing a waste of paper. With the locking device, however, that is automatic in operation, care need not be exercised in the withdrawal of paper as the lock prevents more 120 than the desired movement of the strip.

Having thus briefly described my invention what I claim is—

1. In a printing and serving machine, a printing roll, there being a paper roll formed 125 of a spirally wound strip adapted to be withdrawn in printing contact with the printing roll, withdrawing means therefor, a spring actuated locking device for preventing withdrawal of the strip, a control device on the 130

printing roll adapted to release the locking means to actuation by the spring at predetermined intervals.

2. In a printing and serving machine having a paper roll supported therein formed of a spirally wound strip, a printing roll, means for withdrawing the strip in contact with the printing roll, a releasable means for preventing operation of the withdrawal means, and means carried by the printing roll for automatically actuating the said means to prevent withdrawal of the strip upon the discharge of a portion of the strip bearing the complete printed impression.

15 3. In a printing and serving machine, a printing roll, there being a paper roll formed of a spirally wound strip adapted to be withdrawn in printing contact with the printing roll, means for withdrawing the strip, locking means for said withdrawing means including a spring actuated lever, means on the printing roll preventing actuation of the lever by the spring during the printing operation adapted to release the lever to actuation by the spring upon completion of each printing operation.

4. In a printing and serving machine, a printing roll, there being a paper roll formed of a spirally wound strip adapted to be withdrawn in printing contact with the printing roll, withdrawing means therefor including a hand operated roller provided with a series of teeth at one end, a pivotally mounted lever having an end adapted to engage the said toothed portion to lock the withdrawing roller, a cam rotatable with the printing roll provided with a notch, the opposite end of the said lever riding on the said cam normally preventing locking engagement of the lever with the toothed portion, a spring adapted to draw the lever to notched position, the said notch releasing the lever to actuation by the spring.

5. In a printing and serving machine, a frame work, a printing roll rotatably mounted therein, there being a rotatable paper roll formed of a spirally wound strip adapted to be withdrawn in printing contact with the printing roll to receive successive similar impressions, withdrawing means therefor comprising a hand operated roller and a yieldable roller between which the strip is engaged, rotation of the roller withdrawing the strip and rotating the printing roll, the hand operated roller being provided with a series of teeth at one end, a locking lever pivotally mounted on the frame having one end adapted to engage in locking relation with the said toothed portion, a cam rotatable with the printing roll having a notch, the opposite end of the lever riding on the cam and normally holding the locking end out of engagement with the toothed portion, a spring for drawing the lever to locked relation, said notch in the cam releasing the

lever to actuation by the spring to lock the withdrawing roller at predetermined intervals, and a releasing pin normally engaging the locking end of the lever adapted to force the lever from locking position.

6. In a printing and serving machine, a printing roll, there being a paper roll formed of a spirally wound strip adapted to be withdrawn in printing contact with the printing roll, a manually rotatable roller and means operable in conjunction therewith for withdrawing the strip, a pivotally mounted locking lever, an end of the roller and an end of the lever being formed for locking engagement, a cam on the printing roll on which the opposite end of the lever rides normally holding the locking end of the lever out of engagement with the withdrawing roller, a spring adapted to force the lever to actuation by the spring at predetermined intervals, a hand operated plunger for forcing the end of the lever out of locking engagement with the withdrawing roller, and a retarding device controlled by rotation of the withdrawing roller preventing return of the lever to locking position upon release of the plunger, the retarding means being automatically operable for a period to allow rotation of the cam to position to hold the lever out of locking position.

7. In a printing and serving machine, a printing roll, there being a paper roll formed of a spirally wound strip adapted to be withdrawn in printing contact with the printing roll, a manually rotatable roller for withdrawing the strip, a pivotally mounted locking lever, an end of the roller and an end of the lever being formed for locking engagement, a spring adapted to force the lever to locking position, a cam on the printing roll on which the opposite end of the lever rides normally holding the locking end of the lever out of locking position, said cam being notched to release the lever to actuation by the spring at predetermined intervals, manual means for forcing the end of the lever out of locked engagement with the withdrawing roller, and a retarding device preventing immediate return of the lever to locking position by the spring, the retarding means being automatically operable to hold the lever out of locking engagement until the cam has been turned to normally hold the lever in unlocked position.

8. In a printing and serving machine, a printing roll, there being a paper roll formed of a spirally wound strip adapted to be withdrawn in printing contact with the printing roll, a manually rotatable roller and means operable therewith for withdrawing the strip and projecting the same from the machine, and a locking device for intermittently preventing withdrawal of the strip at the completion of the projection of

each printed portion comprising a pivoted lever, one end of the lever being adapted for locking engagement with the withdrawing roller, a spring for forcing the lever to locking position, a cam on the printing roller engaged by the opposite end of the lever, the cam being formed to release the lever to actuation by the spring at predetermined intervals, manual means for forcing the lever 10 out of locked position, and a retarding device preventing movement of the lever by the spring upon release of said manual means comprising a pivotally supported mem-

ber contacting the said lever, and a latch member pivotally mounted on the said last 15 named pivoted member adapted to assume latched position upon actuation of the manual means, and further adapted to be turned by rotation of the withdrawing roller and release the locking lever after the cam has 20 been turned to hold the lever in unlocked position.

In testimony whereof, I sign this specification.

CLAYTON E. WYRICK,
